OWENS-FORD GLASS COMPANY, OF TOLEDO, OHIO, A CORPORATION OF OHIO

METHOD AND APPARATUS FOR PRODUCING SHEET GLASS

Application filed December 20, 1928. Serial No. 327,235.

The present invention relates generally to the manufacture of sheet or plate glass and more especially to that method wherein the glass sheet is deposited, preferably as it is formed, upon a table or the like from which it is subsequently transferred into an annealing leer.

This invention concerns particularly the transferring of the glass sheet from the table into the annealing leer and has for its principal object the provision of an improved method of and apparatus whereby this transfer of the sheet into the leer may be quickly and conveniently effected and in such a manner that the liability of the sheet being buckled, warped, or otherwise injured during such transfer is minimized, if not entirely eliminated.

Briefly stated, in accordance with the present invention, the glass sheet is adapted to be deposited, as it is formed, upon a substantially horizontal table and carried thereby to a position adjacent an annealing leer. The table is provided with a tiltable top and when the said table is in position adjacent the leer, the top thereof is adapted to be raised or tilted to assume an inclined position whereupon the sheet will be caused to slide from the table downwardly through an inclined plane and onto a plurality of upwardly inclined spaced supporting members or the like which are interposed between said table and leer. As soon as the entire sheet rests upon said members, they are adapted to be lowered to deposit the sheet upon a series of rotatable members or rolls which are actuated to advance the sheet into the leer. The spaced supporting members are preferably rapidly lowered as soon as the sheet is completely supported thereupon so that the length of time the glass sheet rests upon said members may be reduced to a minimum and in order that the passage of the sheet into the leer may be accelerated.

Other objects and advantages of the invention will become more apparent during the course of the following description when taken in connection with the accompanying drawings.

In the drawings forming a part of this application and wherein like numerals are em-

ployed to designate like parts throughout the same,

Fig. 1 is a vertical longitudinal view, partially in section, of glass forming apparatus provided by the present invention,

Fig. 2 is a transverse section therethrough showing the manner in which the sheet is transferred from the table into the annealing leer,

Fig. 3 is an end view of a portion of the transferring means,

Fig. 4 is a detail section taken substantially on line 4—4 of Fig. 2, and

Fig. 5 is a detail view of the stop for the sheets.

Referring to the drawings, 10 designates a receiver or support adapted to receive thereupon a mass or charge of preferably completely refined molten glass 11 from a pot or other receptacle 12. A pair of forming rolls 13 and 14 are positioned in advance of the receiver and are spaced from one another to create a sheet forming pass therebetween, through which the molten glass 11 is adapted to be moved and reduced to a sheet 15 of substantially predetermined and uniform thickness. The receiver 10 is preferably of such size as to receive the entire contents of a single pot 12 thereupon. While the molten glass 11 may be deposited upon the receiver while in a tilted position, as indicated by the full lines in Fig. 1, it is preferred that the glass be deposited upon said receiver while the same is in a substantially horizontal position as indicated by the broken lines after which the pot is removed and the receiver tilted upwardly to advance the glass between the forming rolls 13 and 14. As the glass sheet 15 issues from between the rolls it is adapted to pass downwardly over an inclined runway 16 onto one or a plurality of tables 17. These tables are preferably arranged end to end in abutting relation and are mounted upon wheels 18 running upon tracks 19.

In order to advance the tables beneath the sheet forming mechanism, the said tables may be provided upon their under surfaces with rack bars 20 with which mesh a drive pinion 21 carried by drive shaft 22. Upon rotation of the drive shaft 22 in the direction indi-

cated by the arrow, the drive pinion meshing with the rack bars will effect the desired movement of the tables. Of course, any desired type of drive may be provided for the tables without departing from the spirit of the invention.

The continuous glass sheet 15 issuing from between the forming rolls 13 and 14 is adapted to be cut into individual sheet sections 23, each section being of a length substantially equal to the length of the individual tables. This cutting of the continuous sheet may be effected in any desired manner such as by means of the cutting knife 24 vertically movable in fixed guides 25. Also, it is preferred that the individual sheet sections do not overlap the adjoining ends of any two adjacent tables but that one sheet section be completely supported upon each table. After the sheets have been properly deposited upon the tables, the said tables are adapted to be moved along the tracks 19 to a position adjacent an annealing leer whereupon the sheets are transferred from said tables into said leer. Only a single leer need be used if desired but, on the other hand, production can be greatly accelerated by providing one leer for each table so that the sheets can be simultaneously transferred from the tables into the leers. Also, with such an arrangement, none of the sheets will be permitted to rest upon the tables for an undue length of time to cause an undesirable chilling thereof. Two leers 26 and 27 are herein shown by way of example although, as stated, one or a greater number may be used as preferred. It is with the transfer of the glass sheets from the tables into the leer or leers that the present invention is particularly concerned.

The tables 17 are of a novel construction and as illustrated in Fig. 2, each includes a body portion comprising a bottom 28 having upstanding side portions 29 and end portions 30. Extending between the end portions are the transversely spaced strengthening ribs 31 and 32. The numeral 33 designates the top of the table which is hinged to the upstanding side portion 29 thereof as indicated at 34 so that the top may be raised or tilted upwardly to an inclined position as shown in Fig. 2. To effect this tilting of the table top 33, there may be carried upon the bottom of the table a vertical guide bearing 35 carrying a worm gear 36 internally threaded as shown at 37 (Fig. 4), and adapted to receive therethrough the threaded lifting screw 38. This lifting screw also passes through the guide bearing 35 and has a pivotal mounting as at 39 with the bottom of table top 33. The worm gear 36 is adapted to be driven from a motor 40 through the shaft 41 and worm 42, said shaft being supported intermediate its ends in a bearing carried by the upstanding rib 31.

65 Positioned outside of and in advance of

each leer 26 and 27 is a series of spaced rotatable sheet supporting members or rolls 43 arranged in substantially horizontal alignment and mounted upon shafts 44 journaled at their opposite ends in fixed bearing standards 45 and 46. Each of the roll shafts 44 carries a worm gear 47 meshing with a worm 48 keyed to a line shaft 49 supported by the bearing standard 45 so that upon rotation of said line shaft, the rolls 43 will be driven in unison. Each of the rolls 43 consists of a plurality of sections 50 spaced longitudinally along the shafts 44, the spaces between the sections of the several rolls being in alignment with one another.

Positioned between the last or innermost supporting roll 43a and the respective adjacent leer 26 or 27 is a member 51 arranged parallel with the rolls 43 and mounted upon a shaft 52 journaled at its opposite ends in the standards 45 and 46. The rotation of shaft 52 may be effected from a drive shaft 54 through the worm 55 meshing with the worm gear 56. Carried by or formed integral with the member 51 are a plurality of transversely spaced sheet supporting bars or fingers 53. Upon rotation of shaft 52, the supporting bars or fingers 53 may be swung upwardly to assume the tilted or inclined position as indicated by the full lines in Fig. 2, or they may be lowered to the broken line position indicated in said figure. When the bars are lowered to their substantially horizontal position, they are adapted to be received within the spaces between the sections 50 of rolls 43 as clearly shown in Fig. 3.

In operation, the mass of molten glass 11 is adapted to be initially deposited upon the receiver 10 and subsequently passed therefrom to the forming rolls 13 and 14 by means of which it is rolled into a continuous sheet 15 of substantially predetermined and uniform thickness. The continuous sheet is then cut into sheet sections and deposited upon the individual tables 17 in the manner above described. The tables 10 are then moved along the tracks 19 to a discharging position adjacent the annealing leers 26, 27, etc. When the table is in position opposite the intake end of its respective leer, the supporting rods or fingers 53 are adapted to be tilted upwardly to their inclined position as indicated in Fig. 2. The motor 40 carried by the table is then placed in operation to effect rotation of worm gear 36 which will cause the lifting screw 38 to be moved upwardly to raise the table top to its inclined position. When the table top is raised in this manner, it will be apparent that the glass sheet 23 will slide downwardly therefrom through an inclined plane onto the inclined supporting bars 53. As soon as the entire sheet is supported upon the bars, the said bars are lowered and when this is done the sheet will be deposited or brought to rest

upon the rollers 43, the bars being received between the sections 50 thereof as above stated. The rolls 43 are then adapted to be driven to advance the sheet into the leer wherein it will be supported and carried along upon a plurality of leer rollers 54 or upon any other desired conveying mechanism.

Heretofore, in the transferring of the sheets from the tables into the leer, it has been customary to simply push the sheets from the tables into said leer. This operation has, however, resulted in a tendency for the sheets to be buckled or otherwise marred as they were pushed from the tables which is obviously an undesirable condition. With the present invention, however, it will be apparent that by tilting the top of the table in the manner shown, the glass sheet can slide from the table onto the bars 53 and the bars then lowered and the sheets advanced into the leer. The transfer of the sheets is thus accomplished in an easy and convenient manner and the danger of the sheets being buckled, warped, or otherwise injured will be minimized, if not entirely eliminated.

If desired, a stop member 55 extending transversely of the sheet and having reduced ends 56 vertically movable in guides 57 may be provided to limit the movement of the sheet as it passes downwardly over the supporting bars 53 and the said sheet thereby brought to rest against the stop before said bars are lowered. However, if the sheet is traveling down over the bars at a relatively rapid rate of speed, the contact thereof with the stop may cause a buckling of the former, and this stop is therefore preferably utilized only as a precautionary measure to stop the travel of the sheet should anything happen to prevent the lowering of the bars 53 at the proper time. The reduced ends 56 of the stop 55 are adapted to abut members 58 carried by guides 57 to limit the downward movement of the stop so that there will always be a space between the bars and stop when the said bars are lowered to permit the sheet to pass beneath the stop into the leer.

It is also desirable that the bars 53 be rapidly lowered as soon as the sheet is deposited thereupon so that the translatory downward movement of the sheet over the bars need not be stopped. Thus, the sheet is adapted to be lowered while continuously moving toward the leer. In this manner, the transfer of the sheet into the leer can be accelerated and no means need therefore be provided for stopping the movement of the sheet and which means might be apt to injure or cause a buckling thereof. Also, the more quickly the sheet is deposited upon the rolls 43 and moved therefrom into the leer, the less time the sheet will have to sag or settle between the supporting bars. Of

course, a greater number of bars may be provided positioned closer together if desired.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

We claim:

1. In the manufacture of sheet or plate glass, the steps consisting in forming the sheet and depositing it upon a substantially horizontal supporting surface, and in subsequently tilting said supporting surface to effect the removal of the sheet therefrom.

2. In the manufacture of sheet or plate glass, the steps consisting in forming the sheet and depositing it upon a substantially horizontal supporting surface, and in subsequently tilting said supporting surface to move the sheet to an inclined position where it will slide therefrom.

3. In the manufacture of sheet or plate glass, the steps consisting in forming the sheet and depositing it upon a substantially horizontal supporting surface, transporting the sheet upon said surface to a discharge position adjacent an annealing leer, moving said supporting surface to bring the sheet to an inclined position, passing the sheet from said surface downwardly through an inclined plane, returning the sheet to a horizontal position, and then advancing the sheet into the leer.

4. In the manufacture of sheet or plate glass, the steps consisting in forming the sheet and depositing it upon a substantially horizontal supporting surface, transporting the sheet upon said surface to a discharge position adjacent an annealing leer, raising said sheet upon said supporting surface to inclined position, passing the sheet from said surface downwardly through an inclined plane, lowering the sheet to a horizontal position, and then advancing the sheet into the leer, the lowering of the sheet to the horizontal position being effected while the sheet is in translatory motion.

5. In sheet glass apparatus, a glass supporting table including a body portion and a top pivotally carried thereby, said top being adapted to receive the sheet thereupon while disposed in a substantially horizontal plane, a lifting screw pivotally connected to said top, and means for actuating said lifting screw to tilt the table top upwardly to effect discharge of the sheet therefrom.

6. In sheet glass apparatus, a glass supporting table including a body portion and a top pivotally connected thereto and one of its edges, said top being adapted to receive the sheet thereupon while disposed in a substantially horizontal plane, a lifting screw

carried by the body portion of the table and pivotally connected with the top thereof, a motor also carried by the body portion of said table, and operative connections between the motor and lifting screw whereby upon operation of said motor the table top may be tilted upwardly to effect discharge of the sheet therefrom.

7. In sheet glass apparatus, means for forming the sheet, a glass supporting table having a tiltable top for receiving the sheet thereupon from the forming means, an annealing leer, and means interposed between said table and leer for receiving the sheet from the former and delivering it into the latter.

8. In sheet glass apparatus, means for forming the sheet, a glass supporting table having a tiltable top for receiving the sheet thereupon from the forming means, an annealing leer, and means interposed between said table and leer for receiving the sheet from the former and delivering it into the latter, including a plurality of rotatable members.

9. In sheet glass apparatus, means for forming the sheet, a glass supporting table having a tiltable top for receiving the sheet thereupon from the forming means, an annealing leer, and means interposed between said table and leer for receiving the sheet from the former and delivering it into the latter including a plurality of rotatable members, and means for receiving the sheet from the table and depositing it upon said members.

10. In sheet glass apparatus, means for forming the sheet, a glass supporting table having a tiltable top for receiving the sheet thereupon from the forming means, an annealing leer, and means interposed between said table and leer for receiving the sheet from the former and delivering it into the latter including a plurality of rotatable members, and means adapted to be tilted upwardly to receive the sheet thereupon from the table when the top of said table is also moved to an inclined position and lowered to deposit the sheet upon said rotatable members.

11. In sheet glass apparatus, means for forming the sheet, a glass supporting table having a tiltable top for receiving the sheet thereupon from the forming means, an annealing leer, and means interposed between the table and leer for receiving the sheet from the former and delivering it into the latter including a plurality of horizontally disposed rotatable members, each member including a plurality of spaced roll sections, and a plurality of supporting members adapted to be raised to an inclined position to receive the sheet from the table when the top of said table is also moved to an inclined position and lowered to deposit the same upon the rotatable members, said supporting members when

lowered being received within the spaces between the roll sections.

12. In combination in apparatus for the manufacture of sheet glass, means for forming the sheet, a glass supporting table having a tiltable top adapted to receive the sheet thereupon from the forming means while disposed in a substantially horizontal position, an annealing leer, and means interposed between said table and leer for receiving the sheet from the former and delivering it into the latter including supporting means adapted to be tilted upwardly to receive the sheet from the table when the table top is also in a tilted position, and means for lowering the supporting means after the sheet is deposited thereon.

13. In combination in apparatus for the manufacture of sheet glass, means for forming the sheet, a glass supporting table having a tiltable top adapted to receive the sheet thereupon from the forming means while disposed in a substantially horizontal position, an annealing leer, means interposed between said table and leer for receiving the sheet from the former and delivering it into the latter including a series of rotatable members, and pivotally mounted supporting means adapted to be tilted upwardly to receive the sheet from the table when the table top is also moved to its tilted position and lowered to deposit the sheet upon the rotatable members.

14. In combination in apparatus for the manufacture of sheet glass, means for forming the sheet, a glass supporting table having a tiltable top adapted to receive the sheet thereupon from the forming means while disposed in a substantially horizontal position, an annealing leer, means interposed between said table and leer for receiving the sheet from the former and delivering it into the latter including a series of rotatable members, a plurality of spaced supporting bars pivotally mounted at the end of the series of members adjacent the leer, said bars adapted to be raised to an inclined position to receive the sheet from the table when the top of said table is also moved to its tilted position and adapted to be lowered to deposit the sheet upon said rotatable members, and means for rotating said members to advance the sheet into the leer.

15. In combination in apparatus for the manufacture of sheet glass, means for forming the sheet, a glass supporting table having a tiltable top adapted to receive the sheet thereupon from the forming means while disposed in a substantially horizontal position, an annealing leer, means interposed between said table and leer for receiving the sheet from the former and delivering it into the latter including a series of rotatable members, each member including a plurality of transversely spaced roll sections, a plu-

rality of spaced supporting bars pivotally mounted and adapted to be tilted upwardly to receive the sheet from the table when the top of said table is also inclined and adapted to be lowered to deposit the sheet upon said members, and means for rotating said members to advance the sheet into the leer, said bars when lowered being received within the spaces between the roll sections.

10 Signed at Toledo, in the county of Lucas and State of Ohio, this 18th day of December, 1928.

JOHN L. DRAKE.
